(57) CLAIM

I claim the ornamental design for a shingle retaining clip with clamp, as shown and described.

DESCRIPTION

FIG. 1 is a top perspective view of a shingle retaining clip with clamp showing my new design;

FIG. 2 is a front elevation view thereof;

FIG. 3 is a left side elevation view thereof;

FIG. 4 is a rear elevation view thereof;

FIG. 5 is a right side elevation view thereof;

FIG. 6 is a top plan view thereof;

FIG. 7 is a bottom plan view thereof; and,

FIG. 8 is an perspective view thereof with environmental subject matter depicting how shingle retaining clip with clamp is used to retain and clamp roof shingles.

The broken lines depict unclaimed environmental subject matter that forms no part of the claimed design.
